UNITED STATES PATENT OFFICE

FRANK J. WIDMAN, OF OAK PARK, ILLINOIS

STOKER

Application filed September 19, 1925. Serial No. 57,358.

This invention has to do with improvements in grates and the means for constructing and operating such instrumentalities whereby to automatically advance fuel thereon and to uniformly spread such fuel thereover.

One object of the invention is to provide a step action for a grate having a plurality of pivoted grate-bars, and which may be manually or power operated to feed fuel from one end to the other end, and to discharge the consumed fuel therefrom.

A second object of the invention is to provide a means adapted to advance fuel upon an inclined grate free from back up or resistance.

A third object of the invention is to provide a novel arrangement of grate faces which will not sift fuel or become clogged and which have interlocking portions preventing loss of fuel during stoking.

Another object of the invention is to provide a direct flow of air through the movable blocks forming the grate and thus further increase the efficiency of the boiler.

The invention resides in the combination and arrangement of parts whereby the above objects and certain other objects hereinafter appearing are obtained, as set forth in the following specification and particularly pointed out in the appended claims.

These objects of the invention, and such other objects as may hereinafter appear, are attained by the novel construction of the several elements of the device, the combination of these elements, and the arrangement of these parts one to another. One embodiment of the invention is illustrated in the accompanying two sheets of drawing, hereby made a part of this specification, and in which

Figure 1 is a longitudinal section of a boiler furnace with the grate installed therein shown in elevation;

Figure 2 is a sectional view through the grate, such as would be taken on the line 2-2 of Figure 4, looking in the direction of the arrows;

Figure 3 is a large sectional view of the

grate, similar to that in Figure 2, showing the movable portions thereof in the positions which they assume when the fuel is being advanced;

Figure 4 is a fragmentary top view of a grate embodying the invention;

Figure 5 is a fragmentary perspective view showing the step arrangement of the grate when in stoking position; and

Figure 6 is a perspective view of one of the grate blocks.

Like reference characters are used to designate similar parts in the drawings and in the description which follows.

A conventional boiler structure is shown in Figure 1. In this figure, a grate 10 is disposed between the side walls of the fire box 11 about a boiler, designated 11^a. It will be noted that the grate 10 is obliquely inclined downwardly from the front of the fire box 11 to the rear thereof. The proper inclination to procure correct feeding of coal or other fuel upon said grate 10 is a matter of detail, and it is later to be pointed out that at no time are the sections of which the grate 10 is composed moved into a position so that the angle of their inclination is toward the front of the furnace in which used.

As disclosed in the drawings, the furnace has a conventional fuel door, hereinafter called the firebox door. The grate 10 begins at the front of the furnace just beneath such door and extends toward the rear thereof terminating beneath the boiler 11^a adjacent a dumping section. Beyond such dumping section, in a transverse wall of the furnace, is an ash pit door, the principal portion of ashes being dumped or dropped beneath the dumping section just referred to. As the invention resides in the stoker-grate 10 illustrated, and the furnace structure may well be modified to accommodate the stoker-grate, the structure of the furnace walls, and other parts, is given in no great detail.

Grate 10 comprises a plurality of transverse grate bars 12 and 12^a in parallelism and equidistantly disposed. Each of said bars 12 and 12^a comprises a generally parallelopiped body terminating at each end in

a round lug or pivot bar. For convenience the lug ends of both members 12 and 12^a are designated 12^b. (Reference should be had to Figure 4.)

5 Members 12 and 12^a are alternatively arranged. These members are identical in structure and mounting but differ in the manner of their operation as will shortly be pointed out.

10 Said members 12 and 12^a are at their lug ends journalled in side members 13, of suitable fire resisting material, the ends 12^b being seated in apertures 13^a in said side members. Side members 13 are closely contiguous the side walls of the firebox 11. About 15 each aperture 13^a, the material of member 13 is reinforced as indicated at 14.

Member 13 may be like an I-beam, properly modified in structural details to support the grate bars 12 and 12^a, and to supply a solid foundation for said bars, the grate, and the load carried upon such grate. At each end, transverse members 15 connect side members 13, and the whole grate 10 is supported upon two beams or supports 16 which are closely contiguous to the walls of furnace 11 and which are of sufficient strength to provide a solid foundation for the grate 10.

30 As hereinbefore indicated the grate 10 is inclined longitudinally of the fire box. Beams 16 may rest upon the floor of the ash pit in order to prevent undue strain upon the furnace walls or the necessity for unduly reinforcing such walls.

35 Members 12 each have a depending arm 17. A single bar 18 is pivotally secured to all of arms 17. To member 12^a, a shorter depending arm 19 is secured. All of arms 19 are pivotally secured to a bar 20, similar to member 18.

40 Pivots secured to bar 18 is a shaker bar 21 and a similar shaker bar 22 is attached to member 20. Shaker bars 21 and 22 extend forwardly, in parallelism, through the furnace front, in apertures provided therefor, and are joined to a vertical lever 23, pivotally mounted in a bracket 24 upon the front of the furnace. A handle 25 secured to lever 23 permits of the rocking of said lever 23 to move shaker bars 21 and 22 in opposite directions. The bars 12 and 12^a are thus made to rock toward and away from one another upon the pivot lugs 12^b.

45 In Figures 1 and 2, the normal positions of members 12 and 12^a are shown. In Figure 3, the extreme stoking position therefor is illustrated. It will be noted that the parallelism existing between members 12 and 12^a in normal position is destroyed, and that the adjacent surfaces of said members become obliquely disposed. It is quite manifest that other mechanism could be devised for rocking the bars 12 and 12^a.

50 Reference should now be had to Figures

4, 5 and 6. Figures 4 and 5 show members 30, or grate-blocks, individually illustrated in Figure 6, correctly disposed upon bars 12 and 12^a. As to disposition on a bar 12 or a bar 12^a, members 30 are alternatively reversed, and so that the long section of each member 30 is adjacent the short section of the contiguous member 30.

55 On adjacent cross bars 12 and 12^a, the arrangement of members 30 is complementary, so that a short section of one member 30 always abuts the long section of the member 30 arranged at the side thereof. A complete grate surface is thus provided, such surface being substantially coextensive with the side members 13.

60 Upon rocking the members 12 and 12^a in the manner herein provided or in any other way, the flat surface of grate 10, as disclosed in Figures 1 and 3 is changed to the step arrangement shown in Figure 2. Fuel is thus "stepped" down from the front end of grate 10 to the dumping bars by actuation of lever 23. But it will be noted that each member 30 possesses unique characteristics. Said member comprises a long section 31 and a short section 32.

65 Section 31 comprises a slotted top 33 from which top a body section depends. Such body comprises a skirt section 34 open at the bottom. It also has a rounded and grooved end 35 and at the arbitrary dividing line between it, and the short section, a vertical transverse slot 36 is formed, said slot 36 being in that portion of the block 30 which directly engages and rests upon the bars 12 and 12^a.

70 The length of the wall of slot 36 is greater on the side adjacent section 31 and of considerable less length on the short section (32) side. Said short section has an extending lip 37 which is adapted to fit snugly into the grooved portion of the rounded end of section 31 of an adjacent grate-block adjacent its top.

75 Lip 37 may have considerable overhang and may have a passage 38 therethrough for the circulation of air, the air passing therethrough being admitted to the fire box through slotted top 33.

80 When stoking, parallel trains of blocks 30 affect the fuel on grate 10. The first train or horizontal row of blocks 30 has its ends 31 nearest the fuel door while the adjacent train of blocks 30 is laid on the bars 12 and 12^a so that the sections 32 thereof are nearer the fuel door. The fuel is stepped down by the series of two trains of blocks 30, and as the two trains of blocks have non-parallel top surfaces, the fire is broken and thoroughly stoked, as with each stoking operation, the fuel is stepped downwardly upon the inclined grate 10.

85 At no time can the tops 33 of blocks 30 in either train present a surface inclined to-

ward the door of the furnace. Hence the stepping down action is free from resistance and is always from either a horizontal surface to a rearwardly inclined surface or from a rearwardly inclined surface to a horizontal surface. At no time is the fuel for movement required to "climb" or go "up hill".

On account of the blocks 30 being placed in alternate directions upon the grate bars, it is obvious that at the front and rear of the grate 10 a small portion would be uncovered by a grate block if the former type of block were used throughout. For this reason I provide a specially designed block 130 (Figure 4), having a sufficiently long end section to fill up the gap which would otherwise exist. This provision is not necessary, however, since the style of block indicated by the reference character 30 can be used throughout. I believe, however, that better results are obtained if the blocks 130 are used in the manner indicated, thereby furnishing a substantially continuous surface for supporting the fire.

It is quite manifest, too, that the air circulation through blocks 30 is direct from the front ash pit door to the take-off. The skirt 34 allows direct access of the air to the fuel upon the grate 10 and at no time does the air have to travel in a direction from the back of the furnace to the front. Uniformly the path of air is from the front to the take-off, and this is true whether the grate 10 is in normal position or is at the extreme of a stoking operation.

From the grate 10, the ashes are stoked onto dump bars 40 which are integral with or connected to a transverse pivoted body 41 which is journalled at 42 in the walls of the furnace. A shield or wing 43, arcuate in vertical cross section and coextensive with grate 10, extends across the front of dump bars 40.

An arm 44 is secured to body 41 and is pivoted to a link 45 extending to the front of the furnace where it is pivotally connected to a dump bar lever 46 which is mounted for oscillatory movement on a bracket 47 which may be secured to the front of the furnace.

When dumping is desired, the lever 46 is rocked as is usual. When bars 40 are other than horizontal, the apron 43 abuts the end of grate 10 and prevents fuel on said grate from dropping into the ash pit. Fuel can, therefore, except in inconsiderable quantities, only be discharged into the ash pit from dump bars 40, and dump bars 40 moved only at the will of the fireman. Ashes or fuel disturbed by stoking can only be advanced to dump bars 40 when said bars 40 are in their normal and horizontal position.

I claim:

1. A grate comprising an inclined frame, transverse bars arranged therein in a step-

down relation, a plurality of fuel supporting members upon said bars and having the point of their suspension thereon adjacent one end and normally providing a continuous flat inclined single plane fuel holding surface, said fuel supporting members being arranged upon said bars in linear rows, each row having all its members pointed in one direction, the direction of the members in alternate linear rows being opposite, and means for rocking contiguous transverse bars in opposite directions, the movement of said bars dividing the top surface of said grate into two series of alternately disposed contiguous step-like transverse surfaces having complementary and interfitting contiguous edges, one series of said surfaces being in a transverse horizontal plane and the other series of surfaces sharply inclined inwardly of the grate.

2. In combination, an inwardly inclined grate comprising transverse supports in step-down order, and grate blocks upon said supports, each of said blocks having a curved end the periphery of which is coincident with the arc of the circle described with the axis of said supports as a center, and said blocks normally forming a continuous, flat, inclined grate surface and being arranged in linear rows, all of the members in a single row pointing in one direction, the contiguous rows of said blocks having the members therein pointed in opposite directions, the said supports when rocked in opposite directions providing in said grate a continuous step-like surface of blocks comprising transverse sections each having the abutting blocks thereon pointed in opposite directions, part of which sections are in a horizontal plane and the remainder sharply inclined inwardly.

3. In combination, a grate comprising cross bars pivoted at their ends spaced equally one from another and in step-down order, and grate blocks thereon, each block being supported at a point removed from the center thereof and in normal position providing with contiguous blocks a continuous inwardly inclined grate surface in a single plane, each of said blocks having one curved end, the periphery of which is coaxial with the pivots of the cross bar on which it is disposed, said blocks being a part of a series of longitudinal end to end rows the blocks in any linear row being unidirectional and the direction of the blocks in contiguous rows being opposite, each of said blocks having at its other end a lip adapted to slidably engage upon the curved end of the contiguous block whereby to provide a continuous series of transverse surfaces for said grate when alternate cross bars are rocked in opposite directions, each of said transverse surfaces having edges comprising projecting and receding portions complementary to and interfitting with the adjacent transverse surfaces.

4. In combination, an inclined grate com-

prising a plurality of spaced apart cross bars, 5
grate blocks, each of which is supported upon a cross bar by means adjacent one end of the block, said blocks being arranged in longitudinal rows all of the blocks in a single row pointing in one direction, said rows of blocks being arranged so that the members in one row point in opposite directions from the members in the next contiguous rows, said 10 cross bars being arcuately movable and normally disposed at an angle away from the perpendicular, movement of said rows of blocks conjointly with said supports being adapted to change the planes of the surfaces 15 of said rows of blocks from a normally inclined flat plane with all top surfaces of said blocks upon each bar parallel to the top of said grate to two series of transverse flat surfaces in staggered relation, one of said series 20 of staggered surfaces comprising blocks upon alternate bars being horizontal and alternate with the other series of surfaces, the other series of surfaces comprising blocks on the other bars being sharply inclined toward the 25 bottom of said grate and cooperating with said horizontal series to provide a continuous and unbroken series of transverse surfaces from one end of the grate to the other.

5. In combination, a grate having transverse grate bars arranged in step-down order, 30 rocking means for said bars and adapted to rock said bars from the perpendicular to an angle approximately forty-five degrees therefrom, stop means for limiting the movement of said bars to angles from the vertical to forty-five degrees therefrom, and blocks upon said bars, each block having a slot therein whereby to seat it upon a grate bar, said slot dividing said block into unequal sections, the 35 larger section having its end rounded to provide the body of the block, the smaller section having an end with a short lip, said blocks being arranged in series of longitudinal rows each row comprising members facing in one 40 direction and having the lip end of one block in engagement with the rounded end of the contiguous block to provide a continuous unbroken top surface for the grate, each alternate row of blocks having the blocks therein 45 oppositely directed, said blocks being adapted to be moved concurrently with said bars between the angles indicated and when so moved being adapted to form two series of blocks alternately directed the ends of which 50 interlock to provide a continuous stepped down surface from one end of said grate to the other.

FRANK J. WIDMAN.
